COIN-FREED MACHINE

Percy Stephen Harper, Croydon, England

Application June 13, 1935, Serial No. 26,443
In Great Britain November 9, 1934

3 Claims. (Cl. 312—70)

This invention relates to coin-freed mechanism for automatic delivery machines of the kind wherein the articles or packets stored in the machine are delivered without the necessity of 5 manual operations (after insertion of the coin) through the medium of a rotary packet-retaining device disposed laterally at the foot of the packet chute, normally supporting the packet stack, and movable under escapement control— 10 when a coin has been inserted—to slide off and deliver the lowermost packet.

In this kind of delivery mechanism the weight of the stack even up to the weight of the last packet is utilized to effect delivery by gravity 15 when retaining mechanism has been released by the passage of a coin. The word "packet" covers any article which is advantageously of rectangular or square shape in plan and elevation, such as a packet of cigarettes. In referring to the weight of the stack it is to be understood that this may be augmented by a "follower" weight of any suitable shape or size resting on top of the stack. The lowermost packet overhangs the supporting pocket in the rotary retaining device, and is prevented from tilting and falling into a 20 delivery chute by virtue of the pressure of the superimposed stack distributed uniformly over its upper surface.

According to the said invention the rotary packet-retaining device is constructed with a 30 series of circumferentially spaced rods, rollers or equivalents disposed or projecting parallel to its axis of rotation the angular spaces between the radii connecting each pair of adjacent rods respectively constituting a supporting and delivering pocket for a corner of the lowermost packet.

By this construction a comparatively large 35 diameter rotary device is practicable so that the actual supporting rod or the like on which the underneath surface of the lowermost packet rests can be brought out well towards the middle of the column away from the pocketed corner to reduce the amount of overhang. In addition the 40 following up rod abuts the vertical wall of the pocketed corner from start to finish of the delivery operation. The dimension of the packet portion reposing in the pocket vertically increases, and the width from the pocketed corner to the 45 underneath support line decreases during delivery movement; the present construction allows this variation to be accommodated whilst continuously retaining the two-point abutment by the adjacent rods of the pocket. Further, when the 50 packets being delivered are of a compressible 55

nature (e. g. packets of cigarettes) the construction according to the invention permits the pocketed corner to bulge slightly out of the true right-angle, which assists greatly in retaining the lowermost packet against accidental or fraudulent delivery. Furthermore, the overhanging corner of the lowermost packet need not necessarily be supported or guided.

An embodiment of the invention is illustrated by way of example in the accompanying drawing, wherein:

Figure 1 is a sectional elevation;

Figure 2 is an outside elevation to show one form of escapement which may be employed;

Figure 3 is a fragmentary view showing one 15 end viewed frontwise, of the rotary retaining device; and

Figure 4 is a view similar to Figure 3 of a modification.

In the drawing the column in the machine for holding the stack of packets 5 is designated 1 and the delivery chute for packets released from said column is marked with the reference numeral 2. The rotary retaining device as a whole is designated 3, and 4 is a coin-chute leading 20 from any suitable coin selecting, rejecting and testing mechanisms, not shown.

The delivery chute 2 is bent or formed in any suitable way to throw out released packets as may be desired and the device 3, if preferred 30 may be disposed across the front of the column 1.

The rotary device 3, in the form illustrated, consists of end plates 6 jointed together by a suitable number of circumferentially spaced rods or rollers 7 which have a radial clearance from a hub 8. The end plates are rotatably mounted between the side frames or plates 9, and the axis of rotation 3' of the device 3 is approximately in line with the front or rear wall of the column 1, depending upon whether the device 3 is disposed at the front or the rear of said column. In the example shown the rotary device is disposed below the rear vertical wall of the column 1. Its axis is laterally across the column 1 and sufficiently low for the topmost rod 7 to abut the vertical face of the lowermost packet as shown. The radial and circumferential spacing of the rods 7 is in such relation to the size of the packets 5 that whilst one rod occupies the abutting position just described, the adjacent rod in front lies underneath the lowermost packet as far along as possible. It is practicable to construct the device so that this latter rod is located at about the middle of the packet, and so to reduce the 45 50 55

over-hang, (represented by the right-hand part of the packet in Figure 1).

The weight of the stack of packets 5 is imposed on the particular rod 7 for the time being occupying the supporting position beneath the lowermost packet 5. On release of the device 3, by means of a coin dropping down the chute 4 on to the escapement lever 10, the weight of the stack rotates the device 3 by one step under the control of the escapement 11, the lowermost packet is released and the stack again takes up the position illustrated in full lines. It will be noted that the lowermost packet is entirely clear of the back and front of the column 1.

15 The broken lines illustrate three progressive positions of a packet being delivered. Until the device has turned one complete step (the angular distances between adjacent rods 7) the bottom packet 5 is always horizontal and flush with the superimposed packet; the follower rod 7 rides up the vertical face of the packet whilst the underneath rod 1 moves towards the corner A of the packet. On the conclusion of the partial rotation of the device 3 the bottom packet 5 tilts as shown and drops into the chute 2.

20 The variation of position of the corner A during delivery is allowed for by the "open" form of pocket constituted by the angular space between adjacent pairs of rods 7. Further if, by virtue of the compressibility of the packets 5, the rods 7 press into the material of the packets, the corner A will develop a relative bulge out of the true right-angle, and this distortion, is useful in helping to "lock" the corner A in its 35 pocket.

25 The rods need not extend completely across the device 3. In Figure 4 it will be seen that the end plates 6 each have a set of abbreviated rods, rollers or pegs projecting laterally; those on one disc will be in axial alignment respectively with those on the other disc. The function is exactly the same as in the previous construction, the difference being that the packets 5 are not supported completely from side to side.

30 45 I claim:—

1. In a vending machine, a magazine for a stack of articles to be dispensed, said magazine having inner and outer walls, and means for

successively dispensing the lowermost of a stack of articles contained in said magazine, said means comprising a spaced pair of axially aligned disks mounted below said magazine for rotation about a horizontal axis approximately aligned with the inner wall of said magazine, an annular series of equally spaced apart horizontally disposed rods extending between and rigidly connected with said disks for rotation therewith and to be moved successively beneath the successive lowermost articles of the stack, the spacing of said rods being such that when any given rod is disposed beneath the lowermost article of the stack the next succeeding rod is disposed behind said lowermost article to engage and slide the same forwardly over the first mentioned rod as the dispensing means is rotated, and means controlling rotation of said disks and rods to predetermine the number of articles dispensed during each cycle of operation of the machine.

2. In a vending machine, a magazine for a stack of articles to be dispensed, and means for successively dispensing the lowermost of a stack of articles contained in said magazine, said means comprising a disk mounted below said magazine for rotation about a horizontal axis, an annular series of equally spaced apart horizontally disposed rods rigid with said disk for rotation therewith, the axis of rotation of said disk being approximately aligned with the inner wall of said magazine so that said rods are movable successively beneath the successive lowermost articles of the stack and the spacing of said rods being such that when any given rod is disposed beneath the lowermost article of the stack the next succeeding rod is disposed behind said lowermost article to engage and slide the same forwardly over the first mentioned rod as the dispensing means is rotated, and means controlling rotation of said disk and rods to predetermine the number of articles dispensed during each cycle of operation of the machine.

3. The combination as set forth in claim 2 in which the means controlling rotation of the disk and rods comprises an escapement member 40 cooperating with said rods.

PERCY STEPHEN HARPER.
